UNITED STATES PATENT OFFICE.

OSCAR W. RICE, OF ROCHESTER, NEW YORK, ASSIGNOR TO THE EDWARD J. RICE MFG. CO., OF ROCHESTER, NEW YORK, A CORPORATION.

WATER-CLOSET BEND.

1,152,974.

Specification of Letters Patent. Patented Sept. 7, 1915.

Application filed April 14, 1915. Serial No. 21,346.

To all whom it may concern:

Be it known that I, OSCAR W. RICE, a citizen of the United States, residing at Rochester, in the county of Monroe and State of New York, have invented certain new and useful Improvements in Water-Closet Bends; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in water closet bends and connections and consists of a simple and efficient apparatus of this nature having various details of construction, combinations and arrangements of parts which will be hereinafter fully described, shown in the accompanying drawings and then specifically defined in the appended claims.

My invention is illustrated in the accompanying drawings, in which:

Figure 1 is a side elevation of a bend made in accordance with my invention without waste openings therein. Fig. 2 is a similar view in elevation showing the vent openings. Fig. 3 is a sectional view vertically and longitudinally through the bend and connection. Fig. 4 is a top plan view. Fig. 5 is a view in elevation showing both waste and vent openings. Fig. 6 is a central sectional view through a slightly modified form of the connection and a straight pipe instead of a bend. Fig. 7 is a detail of a slight modification.

Reference now being had to the details of the drawings by numeral, 1 designates a bend having corrugations 2 thereon as guides for cutting off the bend at different locations for fitting purposes. Said bend 45 has a hub 3 with an annular shoulder 4 therein. 5 designates a pipe connection, of lead or other suitable material, the inner circumference of which is flush with the inner surface of the bend, as shown in Fig. 3 of the drawings, and is adapted to rest upon said shoulder. A ferrule, designated by numeral 6, which has its lower end flaring, rests upon said shoulder and into which the lower portion of the pipe 5 telescopes.

When the parts are adjusted as shown in

Fig. 3, an annular space, designated by numeral 7, is formed intermediate the pipe 5 and said ferrule and which is filled with lead, solder or other material, and a filling of lead or other packing material, designated 8, fills the space intermediate the inner surface of the upright portion of the hub and the ferrule, as shown, thus securely anchoring the pipe to the bend and forming a hermetically sealed joint. The coupling ring 9 has an annular flange 10 about the central opening and the wall of said opening is beveled as at 11, leaving an annular space into which the upper end of the pipe 5 is expanded to make a secure connection and over the joint formed intermediate the pipe and connecting ring a suitable packing is provided as a gasket to make a water tight joint. Said ring 9 is of the usual construction as far as its having slots 75 therein for connecting to the closet above in any suitable manner.

In Fig. 1 of the drawings, the bend is shown without any circumferential openings but in Fig. 2 openings 12 for waste connections are shown, and in Fig. 5 I have shown, besides the openings 12, other openings 13 positioned preferably above the longitudinal center of the straight portion of the bend and which are vent openings.

In Fig. 6 of the drawings, I have shown a slight modification of my invention in which the pipe 14 is straight and is provided with the waste openings 15 and a hub 16 with an annular groove 17 therein, and 18 is a circumferentially threaded pipe which telescopes within the hub and is held securely in place by means of a filling or packing 19 which engages the annular groove and the thread of the pipe 18. A connecting ring 20 is mounted upon a threaded portion of the pipe 18 in a similar manner as shown in Fig. 3. It will be noted upon reference to the drawings that each bend terminates in a beading 1' which is provided for the purpose of protecting the bends from damage when being shipped or handled and which may be severed therefrom when the bend is connected up.

In Fig. 7 of the drawings, I have shown a slight modification of my invention adapting the same for use in connection with the Durham system and in which the pipe 1^a is provided with a hub having interior threads 1^b which engage the threads of the connect-

ing pipe 5', otherwise the construction is similar to that disclosed in the other figures of the drawings.

From the foregoing, it will be noted that, by the provision of a bend made in accordance with my invention, the pipe 5, after being measured to the proper length, may be securely fastened to the hub end of the bend in the manner shown, while the connecting ring, through which the pipe 5 passes, is secured to the under surface of the closet and the upper end of the pipe flared outwardly to make a tight joint and, when the parts are thus assembled, they will be rigidly held in place.

While I have shown a particular detailed construction of apparatus involving the features of my invention, it will be understood that I may vary the same to meet different conditions for fitting without in any way departing from the spirit of the invention.

What I claim to be new is:—

1. A water closet bend and connection, comprising a bend with a hub portion, a

flaring ferrule resting upon the shoulder of the hub portion, a pipe telescoping within said ferrule and resting upon the shoulder of said hub portion, a filler intermediate the pipe and ferrule and between the latter and the wall of the hub portion.

2. A water closet bend and connection, comprising a bend with a hub portion, a flaring ferrule resting upon the shoulder of the hub portion, a pipe telescoping within said ferrule and resting upon the shoulder of said hub portion, a filler intermediate the pipe and ferrule and between the latter and the wall of the hub portion, a ring having an opening with a flange about the same, the wall of the opening being beveled a part of its width and adapted to receive the upper expanded end of the pipe.

In testimony whereof I hereunto affix my signature in presence of two witnesses.

OSCAR W. RICE.

Witnesses:

FRANKLIN H. HOUGH,
A. R. FOWLER.
